INVENTOR

William Scott

United States Patent Office.

WILLIAM SCOTT, OF PLYMOUTH, MICHIGAN.

Letters Patent No. 70,475, dated November 5, 1867.

IMPROVEMENT IN CARRIAGE-SEAT SPRING.

The Schedule referred to in these Letters Patent and making part of the same.

TO WHOM IT MAY CONCERN:

Be it known that I, WILLIAM SCOTT, of Plymouth, in the county of Wayne, and State of Michigan, have invented a new and useful Seat-Spring: and I do declare that the following is a true and accurate description thereof, reference being had to the accompanying drawings, and to the letters of reference marked thereon, and making a part of this specification.

Figure 1 is a view of a common box, partly in section, showing my invention attached thereto.

Figure 2 is a sectional view of my spring upon the line $x-x$ in fig. 3.

Figure 3 is another sectional view of the same.

The same letters refer to similar parts in each figure.

The design of this invention is to furnish a cheap and durable spring for seats of all kinds.

I use a spiral spring, A, of any desired strength, the bottom of which is inserted into the socket B. The socket B is attached to a plate, C, provided with a circular flange, D, which hooks upon the top of the box of the wagon. The socket, plate, and circular flange may be made of any desired metal.

I have described my invention as applied to an ordinary wagon, while the same kind of spring and socket, with or without the plate and circular flange, may be used for seats of any kind.

What I claim as my invention, and desire to secure by Letters Patent, is—

The arrangement and combination of the spiral spring A, the socket B, and the plate C, provided with the circular flange D, substantially as described for the purpose designed.

WILLIAM SCOTT.
